UNITED STATES PATENT OFFICE.

GEORGE MAYERLE, OF SAN FRANCISCO, CALIFORNIA.

DESIGN FOR AN OPTICIAN'S TOOL.

53,599.

Specification for Design.

Patented July 15, 1919.

Application filed February 12, 1919. Serial No. 276,661. Term of patent 3½ years.

To all whom it may concern:

Be it known that I, GEORGE MAYERLE, a citizen of the United States, residing in the city and county of San Francisco and State of California, have invented a new, original, and ornamental Design for an Optician's Tool, of which the following is a specification, reference being had to the accompanying drawing, forming part thereof.

The figure is a perspective view of an optician's tool, showing my new design.

I claim:

The ornamental design for an optician's tool, as shown.

GEORGE MAYERLE.

Witnesses:

JOHN H. HERRING,
G. W. BALL.
